UNITED STATES PATENT OFFICE.

JAMES H. PETERSON, OF PRICE, UTAH, ASSIGNOR TO THE PETERSON-CULP GEARLESS STEAM AUTO COMPANY, OF DENVER, COLORADO, A CORPORATION OF COLORADO.

STEAM-GENERATOR.

1,317,388.

Specification of Letters Patent. Patented Sept. 30, 1919.

Application filed July 21, 1917. Serial No. 182,048.

To all whom it may concern:

Be it known that I, JAMES H. PETERSON, citizen of the United States, residing at Price, county of Carbon, and State of Utah, have invented certain new and useful Improvements in Steam-Generators; and I do declare the following to be a full, clear and exact description of the invention, such as will enable others skilled in the art to which it appertains to make and use the same, reference being had to the accompanying drawings, and to the characters of reference marked thereon, which form a part of this specification.

My invention relates to improvements in steam generators, my object being to provide a construction of this class which shall have a large capacity as compared with its bulk, and which at the same time may be easily and quickly repaired. Hence, the construction is well adapted for automobile use in connection with an engine operated by steam.

To be more specific, the generator consists of a body member composed of upper and lower perforated plates connected by water tubes, the extremities of these tubes being secured to the plates and registering with certain of the perforations in the latter, the length of the tubes being sufficient to give the desired generating capacity, the water tubes being suitably distributed in the fire space between the said plates. Above the uppermost plate of the body member is a second perforated plate, the perforations registering with a second set of perforations in the top of the body member, said second set of perforations being arranged and distributed between the perforations with which the extremities of the water tubes are in communication. Short fire tubes are inserted through the openings of the second plate and connected with the said second set of perforations, in the top plate of the body member, the fire tubes being surrounded by spacing sleeves which space the top plate of the body member from the second plate, thus forming a steam chest for the generator. Below the lowermost plate of the body member and perforated to correspond with a second set of perforations in the bottom plate of the body member, is a fourth plate having perforations through which are passed fire tube

members, whose upper extremities are secured in a second set of perforations of the bottom plate of the body member, but being applied to the short fire tubes and screwed against the second and fourth plates respectively whereby the said plates are held in place, spacing sleeves being arranged between the lowermost plate of the body member and the fourth plate, whereby a water jacket is formed which is in communication with the water tubes of the body member and consequently, with the steam chest above. Provision is made for introducing water to the generator through the medium of a pump which is operated by steam taken from the generator, the supply of steam to the pump being controlled by a float operated valve, the float being located in a vertical tube centrally located and extending through the body of the generator, the water jacket and the steam chest. Furthermore, means are provided for automatically cutting off the passage of fuel to the generator, as the pressure in the steam chest rises beyond a predetermined degree.

Having briefly outlined my improvement I will proceed to describe the same in detail, reference being made to the accompanying drawing in which is illustrated an embodiment thereof. In this drawing:

Figure 1 is a top plan view of the generator shown in horizontal section taken on the line 1—1, Fig. 2.

Fig. 2 is a section taken on the line 2—2, Fig. 1.

Fig. 3 is a side elevation of the generator equipped with an exhaust hood, which is partly broken away, the construction being shown on a somewhat larger scale than in Figs. 1 and 2.

Fig. 4 is a fragmentary view, illustrating the construction for automatically cutting off steam from the pump through the medium of a float-operated lever and valve, the parts being shown on a still larger scale than in Fig. 3.

Fig. 5 is a fragmentary, detail view, illustrating the construction for automatically regulating the supply of fuel to the generator as the pressure in the steam chest varies.

The same reference characters indicate the same parts in all the views.

Let the numeral 5 designate the body of

the generator which consists of perforated top and bottom plates 6 and 7 connected by a series of water tubes 8 which extend through the fire space 9 between the two 5 plates, and are distributed at suitable intervals in said fire space for steam generating purposes. The extremities of these water tubes are secured to the plates 6 and 7 by welding, or in any other suitable manner, 10 whereby the body of the structure becomes a substantially integral device. Arranged above the top plate 6 of the body member is a plate 10 which is perforated to register with perforations 4 in the plate 6, said last 15 named perforations being interspersed between the perforations of the plate 6 in which the upper extremities of the water tubes are secured. Short fire tubes 12 are passed through the perforations in the plate 20 10 and secured in the perforations 4 of the plate 6 by welding or in any other suitable manner. The portions of the short fire tubes 12 which pass through the space 14 between the plates 6 and 10 are surrounded 25 by spacing sleeves 15 whose upper extremities engage the plate 10 and whose lower extremities engage the plate 6. Hence, in case it is necessary to gain access to the generator for purposes of repair, the top plate 30 35 may be removed by unscrewing nuts 13 applied to the upper extremities of the fire tubes 12, and when this is done it is evident that it will be easy to remove a short fire tube 12 and substitute a new one in the event 40 45 that this should be necessary, since the inner extremity of the fire tube may be easily drilled out. The top plate 10 is further secured to the body member of the generator by means of bolts 16 which are passed 50 through the outer portion of the plate 10 and through perforations formed in an exterior flange 17 with which the top plate 6 is provided, the two plates being spaced where these bolts are located by a ring 18 55 which closes the steam chest 14 exteriorly.

Another plate which I will designate by the numeral 19 is arranged below the bottom plate 7 of the body member and spaced therefrom by sleeves 20 which surround perforations 3 in the plate 7 and also surround corresponding perforations 2 formed in the plate 19 and through which short fire tubes 21 are inserted, their upper extremities being secured within the perforations 3 of the plate 7, while nuts 22 are applied to the lower protruding extremities of these short fire tubes 21, whereby the plate 19 is removably held in place.

This spacing of the plates 7 and 19, forms 60 a water jacket 23 through which all of the short fire tubes 21 pass. The bottom plate 7 of the body member extends beyond the fire space and water tube portion thereof and is secured to the outer portion of the plate 19 65 by bolts 24 passed through registering open-

ings formed in the connected parts, nuts 25 being applied to the upper extremities of these bolts, these plates being spaced where these bolts are located by a ring 26 which closes the water jacket on the outside. 70

Below the plate 19 of the generator and in communication with the fire tubes and fire space thereof, is a combustion chamber 27, which as illustrated in the drawing is formed by the employment of a pan or a 75 shell 28 which is connected with the generator proper by means of the bolts 24, which also pass through registering openings formed in an exterior flange 29 formed on the upper edge of the pan and extending 80 outwardly therefrom, the pan having perforations 30 through which air may pass for purposes of combustion. As shown in the drawing, a pipe 31 for supplying fuel to the chamber 27, enters the same and is 85 connected therewith by means of nuts 32 and 33, the said pipe having a seat 34 for a valve 35, whose stem 36 extends upwardly through a perforation formed in the flange 29 of the pan, the upper extremity of the 90 stem entering a hollow member 37 in which is located a spring 38 which acts upon the upper extremity of the stem 36, the upper extremity of this spring engaging a stop within the hollow member 37. The upper 95 portion of the stem 36 is provided with a pin 39 which is movable in a slot 40 formed in the hollow pipe member 37, thus limiting the independent downward movement of the valve 35. Surrounding the hollow member 37 and the exposed portion of the valve stem 36, is a spiral spring 41 whose lower extremity rests upon the outer portion of the flange 29 of the body member of the 100 generator, and whose upper extremity engages a shoulder 42 formed on the hollow member 37. Hence, the spring 41 normally holds the valve 35 in the open position to allow fuel to pass to the combustion chamber 27 through the pipe 31. The upper end of 105 the hollow pipe member 37, extends through an opening 43 formed in the bottom of a cylinder 44 composed of upper and lower members 45 and 46 carrying a packing 47. Within this cylinder is located a piston 48 110 which is secured to the upper extremity of the pipe member 37. Leading from the chamber 49 of this cylinder is a pipe 50 which communicates with the steam chest 14, the pipe 50 being elbow shaped and secured within the ring 18 by nuts 51 and 52 applied to the pipe 50 and engaging the ring 18 on opposite sides thereof. Hence, the steam in the chest 14, acts on the piston 48 and the latter in turn will move downwardly and serve to close the valve 35, when the steam within the chest reaches a predetermined degree. The object of the spring 38 within the hollow pipe member 37 is to provide for further downward movement of 130

the piston 48 after the valve 35 has been closed, without exerting undue pressure on the said valve.

The generator is supplied with water 5 through the medium of a pump 53 which is connected by means of a pipe 54 within the steam chest 14 for the operation of the pump, a nipple 55 being threaded into the top plate 10 of the steam chest and recessed, 10 as shown at 56, to receive a needle valve 57 which is adapted to engage a seat 58 and cut off the supply of steam to the pipe. This needle valve 57 is connected, as shown at 59, with a lever arm 60, the latter being pivotally connected, as shown at 61, with a member 62, which is threaded into the ring 18 of the steam chest and extends beyond the same, the lever arm 60 being pivotally connected with its protruding portion. The 20 outer end of this arm 60 passes through an opening 63 formed in a relatively large central water tube 64, and enters an opening 65 formed in the upper extremity of a stem 66 of a float 67, the float being carried by a 25 rectangular skeleton frame 68 which is freely slidable in the pipe 64, this frame extending below the body of the float, as shown at 69, the lower extremity of this extension engaging a shoulder 70 which forms a stop 30 for the float when it is inserted through the upper extremity of the pipe 64.

This pipe 64 passes centrally through the generator and through perforations formed in the plates 6, 7, 10 and 19, its upper extremity extending above the plate 10 and being secured by means of a nut 71 screwed down upon the plate 10, a reducing nipple 72 being applied to the upper extremity of this pipe above the nut, this nipple being 40 perforated to allow the steam generated to escape for use, a suitable outlet conduit 73 being connected therewith, as shown in Fig. 3 of the drawing. This pipe 64 communicates with the water jacket 23 by means of 45 openings 74 and with the steam chest by one or more openings 63 through one of which the lever arm 60 passes, as heretofore described. This pipe 64 is surrounded where it passes through the steam chest by a spacing sleeve 75, and where it passes through the water jacket by a similar sleeve 76. A pipe member 77 is threaded into the lower extremity of the pipe 64, and passes downwardly through the combustion chamber 27 50 and through an opening formed in the pan 28, its lower protruding extremity being connected, as shown at 78 with an elbow 79 which is connected by means of a coupling 80, with a conduit 81, whose opposite extremity is in communication with the pump 53.

From this it will be understood, that after the generator is started, steam will pass from the chest 14 through the nipple 55 and 65 the pipe 54 to the pump 53 and operate the

latter, whereby water will be supplied to the generator through the conduit 81. This water will rise in the pipe 64 to the same level that it reaches in the water tubes 8 of the body of the generator, and when it 70 has reached a predetermined height it will act upon the float 67 to raise the latter, which in turn will act upon the lever arm 60 to close the needle valve 56 and cut off the steam from the pump, thus stopping the 75 latter until the water falls sufficiently in the water tube portion of the generator to open the needle valve, when the pump will again start, as will be readily understood.

In order to properly confine and carry 80 away the products of combustion as they leave the upper open extremities of the fire tubes of the generator, any suitable provision may be made. In the drawing I have illustrated a hood 86, which is secured to the 85 steam chest portion of the generator and extends above the same a suitable distance, the steam pipe 73 leading from the nipple 72, passing through a perforation in this hood. From the hood a conduit 87 may extend downwardly in order to discharge the products of combustion at any desired or convenient point, as at the rear of the automobile with which my improved generator is employed. The steam chest may be provided with a safety valve 85 which may be of any suitable construction. The upper or outer portion of this valve may extend beyond the hood 86 whereby it will be in communication with the atmosphere. 100

From the foregoing description the use and operation of my improved steam generator will be readily understood. The water jacket and water tubes will be supplied with water from any suitable source with which 105 the pump may be connected, the pump being of any suitable construction. The fuel may also be taken from any desired source, its supply to the combustion chamber of the generator being automatically controlled 110 through the medium of the valve 35, as heretofore described. The steam for operating the pump will be taken from the generator, as heretofore explained, its supply to the pump being automatically controlled 115 through the medium of the float and needle valve construction set forth. The steam generated will be taken from the steam chest through an outlet 73 from which it may be conducted to the engine (not shown) with 120 which the generator is employed.

In the event that repairs are necessary, the top and bottom plates 10 and 19 may be readily detached by removing the nuts applied to their outer extremities. It will, of 125 course, be necessary to detach the other mechanism, which is located outside of these plates, all of which, however, is readily removable and replaceable, as will be readily understood from inspection of the drawing. 130

Attention is called to the fact that there is a check valve 82 in the conduit 81, which will be held closed by the back pressure of the water when the pump is not running. It should be explained that the body of the generator is provided with an outer covering of asbestos, or other suitable nonheat-conducting material, and an outer plate 84 which is applied to the packing 83 and secures the said packing in place for the performance of its function.

Attention is called to the fact that the large, centrally located tube 64, is secured to the plates 6 and 7 of the body of the generator by welding, or in any other suitable manner, while it simply passes through openings in the plates 10 and 19, whereby the last named plates are readily removable from the body of the structure, as heretofore explained.

Having thus described my invention, what I claim is:

1. A steam generator comprising a lower chamber constituting a water jacket and an upper chamber constituting a steam chest, open ended water tubes connecting the water jacket with the steam chest, one of said tubes being substantially centrally located, fire tubes extending through the water jacket and fire tubes extending through the steam chest, a water supply, means to maintain a constant water level at an intermediate point in said water tubes, an operative part of said

level controlling means being mounted in said steam chest, and having a portion depending into said centrally located tube.

2. A steam generator comprising a lower chamber constituting a water jacket and an upper chamber constituting a steam chest, open ended water tubes connecting the water jacket with the steam chest, fire tubes extending through the steam chest and fire tubes extending through the water jacket, a water supply, means to maintain a constant level of the water at an intermediate point in said water tubes, an operative part of said level-controlling means being mounted in the steam chest and having a portion depending into one of said tubes.

3. A steam generator comprising a lower chamber constituting a water jacket and an upper chamber constituting a steam chest, open ended water tubes connecting the water jacket with the steam chest, a centrally located water tube being enlarged, fire tubes extending through the water jacket and fire tubes extending through the steam chest, a water supply, means to maintain a constant water level at an intermediate point in said tubes, an operative part of said means being positioned in said steam chest and having a portion depending into said enlarged water tube.

In testimony whereof I affix my signature.

JAMES H. PETERSON.
